UNITED STATES PATENT OFFICE.

EMILE A. FOURNEAUX, OF NEW YORK, N. Y., ASSIGNOR TO HERMAN A. METZ, OF BROOKLYN, NEW YORK.

AZO COMPOUND AND PROCESS OF MAKING SAME.

SPECIFICATION forming part of Reissued Letters Patent No. 12,330, dated March 21, 1905.

Original No. 728,455, dated May 19, 1903. Application for reissue filed September 29, 1904. Serial No. 227,023.

To all whom it may concern:

Be it known that I, EMILE A. FOURNEAUX, a citizen of the United States, residing at New York, in the borough of Manhattan and State 5 of New York, have invented certain new and useful Improvements in Azo Compounds and Processes of Making Same, of which the following is a specification.

In the application heretofore filed by me 10 on September 16, 1902, Serial No. 123,558, for improvements in azo dyes and processes of making the same, I have shown that the azos derived from diazotized nitroamino compounds and beta-naphthol, which being in 15 soluble are not suitable for the manufacture of lake and pigment colors as such in the finished state, can be made available for this purpose by combining the nitrodiazo compound with beta-naphthol in the presence of 20 a diazo compound derived from an aminosulfonic acid or by the action of a nitrodiazo compound on an azo dye derived from a diazosulfonic acid and beta-naphthol. I have since found that similar and even more valuable substances, which consist in the main of 25 the azo dyes derived from nitrodiazo compounds and beta-naphthol in such an extremely fine state of division that they will react readily with metallic salts, forming 30 lakes, can also be obtained by coupling the nitrodiazo compound with a mixture of beta-naphthol and other phenolic bodies, especially the sulfonic and carboxylic acids of phenols, provided that these latter bodies are used in 35 sufficient quantities. The operation is best conducted in the ordinary way by slowly pouring the solution of the nitrodiazo body into an alkaline solution of a mixture of beta-naphthol and other phenolic body while stirring 40 constantly, the amount of alkali being such that the reaction of the liquid is slightly alkaline after coupling. It is also desirable to use the diazo compound in such a proportion that it will just saturate the total of the 45 phenolic bodies. In other words, for one molecular proportion of the diazo compound it is best to use such quantities of beta-naphthol and the other phenolic body that they sum up to one molecular proportion. Supposing, for

instance, that one molecular proportion of 50 paranitrodiazobenzol and beta-naphthol and beta-naphtholmonosulfonic acid F be used in the proportion of three parts of the former to one part of the latter, it would be advisable to use three-fourths of a molecular proportion of beta-naphthol and one-fourth of a molecular proportion of beta-naphtholsulfonic acid F and a sufficient amount of alkali to insure a neutral or slightly-alkaline reaction of the liquor after the combination has taken place. 55

In the ordinary process of manufacturing lakes from diazotized paranitranilin and beta-naphthol, which consists in mixing a suitable base with the proper amount of an alkaline beta-naphthol solution and then allowing the 60 corresponding amount of a diazotized paranitranilin solution to run into this mixture, thus forming the insoluble azo compound in the presence of the base and precipitating it on the base, it has occasionally been customary to add small quantities of such phenolic bodies as mentioned in this application to the beta-naphthol solution in order to obtain bluer shades; but the amounts added were limited to a very small proportion, usually 65 not exceeding five per cent. of the amount of naphthol used, as the color became partly soluble in water if more was used, which is not desirable in that process. I wish to emphasize that this method has nothing in common with 70 my process but the materials used, nor is the proportion of these materials the essential difference, as the novelty of my process consists in the entirely-unexpected and newly-observed fact that by the addition of such 75 phenolic bodies in sufficient quantities to the alkaline beta-naphthol solution before coupling with the nitrodiazo body the insoluble azo body resulting from the action of the nitrodiazo body on beta-naphthol is precipitated in an entirely new form of such extreme 80 division that it reacts readily with metallic salts, forming thus insoluble lakes and being available for the manufacture of lakes by the same general methods as the soluble azo dyes 85 commonly used for this purpose. This constitutes an essential progress. Whether the soluble azo colors incidentally formed by the 90

action of the nitro diazo compound on the sulphonated or carboxylic phenolic bodies participate in the precipitation when the resulting dye is used for the manufacture of lakes is immaterial. They are merely unavoidable by-products. When it is desired to vary the shade of the resulting body, it is feasible to add other diazo compounds to the nitro diazo compound mainly used; but the total amount of diazo compounds used should be just sufficient to neutralize the total amount of phenols used, as thus the best results are obtained. After the coupling is completed it is usually preferable to add a certain amount of common salt, which facilitates filtering, and to wash the filtered product with a diluted salt solution. The product is then reduced to paste form, in which form it is applied for the manufacture of lakes.

Example 1. One hundred and thirty-eight parts paranitranilin are divided in one thousand parts water containing seventy-two parts of commercial sodium nitrite, and the temperature is lowered nearly to the freezing-point by the addition of ice, when three hundred and sixty parts hydrochloric acid of 20° Baumé are added. The diazo solution thus obtained is filtered and diluted to ten thousand parts at a temperature not exceeding 15° centigrade. One hundred and fifteen parts beta-naphthol are dissolved in the calculated amount of caustic soda and the necessary amount of water. To this solution is added a solution of forty-nine parts of the sodium salt of the naphtholsulfonic acid 2.7 and two hundred and seventy-five parts of calcined sodium carbonate, and the whole diluted to ten thousand parts, maintaining the temperature at not over 15° centigrade. The diazo solution is then allowed to run slowly into the naphthol solution under continuous stirring. The solution is then allowed to stand for several hours, after which salt is added, the solution filtered, and the precipitate washed with a diluted salt solution. The dye is then made into a pulp.

Example 2. A diazo solution is prepared from one hundred and thirty-eight parts paranitranilin, as above. On the other hand, two hundred and twenty parts of paranitranilinorthosulfonic acid are dissolved in boiling water and the solution cooled finally by addition of ice nearly to the freezing-point, and one hundred and seventy parts of hydrochloric acid of 20° Baumé are added and the body diazotized by adding a solution of seventy-two parts of commercial sodium nitrite and enough water to prevent the diazo body from separating in crystalline form. Two hundred and thirty parts of beta-naphthol are dissolved in the calculated quantity of caustic soda and the necessary quantity of water, and a solution of eighty parts betaoxynaphthoic acid dissolved in the calculated amount of caustic

soda, and four hundred and twenty-four parts 65 of calcined sodium carbonate are added, the whole being made up to twenty thousand parts at a temperature not exceeding 15° centigrade. The above diazo solutions are then mixed and the mixture run slowly, while stirring constantly, into the above naphthol solution, then salted, filtered, and washed as in Example 1.

The azo dyes thus obtained can be used in the manufacture of red lake and pigment colors, being essentially composed of paranitrobenzolazobeta-naphthol or a mixture of this body with other beta-naphtholazo compounds, which forms a gelatinous paste that is insoluble in water, but so finely divided as to react readily with metallic salts and produce red 80 lakes having a bluish undertone with a great fastness to light.

I claim—

1. The process herein described of making an azo compound suitable for the manufacture 85 of lake and pigment colors, which consists in coupling a diazo compound with a mixture of beta-naphthol and other phenolic compounds as herein specified, in such proportion that the resulting insoluble azo compound is formed in 90 such an extremely finely divided condition as to be suitable as such for the manufacture of lake and pigment colors, substantially as set forth.

2. The process herein described of making 95 an azo compound suitable for the manufacture of red lake and pigment colors, which consists in coupling a nitro diazo compound with a mixture of beta-naphthol and other phenolic compounds as herein specified in such proportions 100 that the resulting insoluble azo compound is formed in such an extremely finely divided condition as to be suitable as such for the manufacture of lake and pigment colors, substantially as set forth.

3. The process herein described of making an azo compound suitable for the manufacture 110 of red lake and pigment colors, which consists in combining a nitro diazo body and another diazo body with a mixture of beta-naphthol 115 and other phenolic compounds as herein specified in such proportions that the resulting insoluble azo compound is formed in such an extremely divided condition as to be suitable for the manufacture of lake and pigment colors, substantially as set forth.

4. An azo compound suitable for the manufacture of lake and pigment colors, containing an insoluble beta-naphtholazo compound, produced by coupling a diazo compound with 120 a mixture of beta-naphthol and other phenolic compounds as herein specified, and being a gelatinous paste which is insoluble in water but so finely divided as to react readily with metallic salts, producing lakes having great fastness 125 to light, substantially as described.

5. An azo compound suitable for the manufacture of red lake and pigment colors, ob-

tained by combining diazotized paranitranilin with a mixture of beta-naphthol and other phenolic bodies, and consisting essentially of paranitrobenzolazobeta-naphthol, or a mixture of this body with other beta-naphtholazo compounds, forming a gelatinous paste which is insoluble in water and so finely divided as to react readily with metallic salts, and produce red lakes with a bluish undertone having a

great fastness to light, substantially as set forth.

In testimony whereof I affix my signature in presence of two witnesses.

EMILE A. FOURNEAUX.
